ELECTRICAL RESISTOR

Sumner Stern, Levittown, Pa., assignor, by mesne assignments, to the United States of America as represented by the Secretary of the Navy

Application January 28, 1958, Serial No. 711,761

6 Claims. (Cl. 338—116)

This invention relates to electrical circuit contacts and in particular, to improved electrical contactors employed in magnetic relay devices.

Magnetic relays are often used to control contactors in circuits carrying high direct currents. Since direct current flows as the result of a continuous voltage applied to a circuit, it does not pass periodically through zero. Therefore, even in an absolutely non-inductive circuit, the full line voltage is available to maintain the arc that forms at the opening contactors. In addition to the line voltage, there is also an induced voltage generated in any inductance that may form a part of the circuit. This self-induced voltage is in such a direction as to oppose a change in the amount of current in the circuit and, therefore, is in the same direction as the line voltage, and the sum of these two voltages strives to maintain the arc. Arcing results in pitting of contactor surfaces and eventually to contactor failure.

Because arcing shortens the operable life of such contactors and limits the reliability of them, many efforts have been made to reduce this arcing. Some of the methods employed include electromagnetic blow-out, absorption circuits, and double break contactors. All of these result in increased complexity of relay apparatus.

It is a general object of this invention to eliminate arcing of relay controlled circuit contactors.

It is another object of this invention to provide improved relay contactors having a longer operable life and in which contactor pitting is substantially eliminated.

It is a further object of this invention to provide improved relay contactors in which arcing is eliminated without adding to the complexity of the relay device.

These objects are achieved in this invention by providing at least one resilient contactor. This resilient contactor is so designed that when the circuit is opened only a very small area of the contactor touches an associated contactor. For circuit closure the resilient contactor is compressed so that a greater portion of its area touches its associated contactor. The resilient contactor itself has a coated surface which varies in resistance from a very high resistance at the aforementioned small area of contact to a very low resistance when there is a large area contact. Thus, the resistance on the surface of the contactor varies from an extreme approaching insulation to one of good conductivity. The contactors always touch one another even when in the open circuit position and, although the change from closed to open circuit is a rapid one, it is still a gradual change. Because of this gradual change from high conductivity to high resistance no arcing between the contactors can occur.

In a preferred embodiment of the invention a pair of resilient contactors are used. These comprise arcuate springs contacting each other at their centers. One spring is attached to a bracket which is stationary and the other spring is attached to the movable armature of a control relay. One or both of the springs are coated with a resistive material as described above. In a modification of the preferred embodiment the arcuate spring contactors

2

are replaced by cantilever type springs. These cantilever springs are coated so as to provide high resistance at their ends and high conductivity inwardly from the ends. The ends of the springs are maintained in contact at the open circuit position. During compression or release of the cantilever springs a gradual change in resistance between them will again occur and arcing will thus be eliminated.

Other objects and many of the attendant advantages of this invention will be described in greater detail by reference to the accompanying drawings wherein:

Fig. 1 is a side elevation of a magnetic control relay incorporating the improved contactors of this invention; open circuit position is illustrated in solid outline and closed circuit position in dotted outline.

Fig. 2 is a fragmentary view of a magnetic control relay identical to the relay of Fig. 1 but incorporating improved contactors of cantilever design.

Fig. 3a schematically illustrates the variable resistance coating on one or both of the contactors of Fig. 1.

Fig. 3b similarly illustrates the variable resistance coating on one or both of the contacts of Fig. 2.

Similar reference characters are applied to similar elements throughout the drawings.

In Fig. 1 there is shown a control relay having a U-shaped core 11, an energizing coil 12, and an armature 13. The armature 13 is hinged at the pivot 14 and completes a magnetic path closing the open end of the U. The outer end of the armature has fastened to it an arcuate spring 15. Opposite the arcuate spring 15 is a like spring 16 supported by a bracket 17. Each of the arcuate springs 15 and 16 have contact terminals 18 and 19 associated therewith for attaching thereto the leads of the circuit to be controlled. The arcuate springs 15 and 16 are shown in their compressed positions by the dotted outlines 15' and 16'.

In Fig. 3a the contacting surfaces of the springs are shown coated with a conductive material. This conductive material might comprise copper filings suspended in a flexible polystyrene resin.

Another method for constructing variable resistance contacts is described in U.S. Patent 2,060,114, of L. Podolski. The coating is applied to the spring surface in such a manner that conductivity at the center 23 of the spring surface is almost non-existent, that is, the area 23 in the center of the surface is nearly a pure insulator. Moving from the center 23 outward to either end the volume of copper filings in the polystyrene resin is increased until at some area 24 the surface of the spring becomes a good conductor. It can be seen that when two of these springs are juxtaposed, as shown in Fig. 1, their contact at open circuit condition will amount to a near perfect insulator and will therefore open the circuit connected to the terminals 18 and 19. When the springs are compressed by the energization of the relay, an increasingly greater portion of the better conductive area of one spring will come in contact with a like area of the other. Hence, when the armature is fully attracted to the core, the contact surfaces of the two springs are compressed until the highly conductive areas are touching each other to complete the circuit between the two terminals 18 and 19.

In a modification, shown in Fig. 2, cantilever springs 30 and 31 might well be considered to comprise the left half of the two arcuate springs shown in Fig. 1. As before, the cantilever springs are connected to terminals 32 and 33 which are in the circuit to be controlled. A similar coating is applied to the contacting surfaces of cantilever springs 30 and 31. This coating is illustrated in Fig. 3b and might well be considered as comprising the left half of Fig. 2. In operation the cantilever springs

shown in Fig. 2 function in an identical manner to that of the springs in Fig. 1.

By incorporating the improved spring contactors of this invention in a relay controlled circuit, arcing is completely eliminated regardless of the speed at which the relay operates. This provides for a greatly increased life span and highly improved reliability.

Obviously many modifications and variations of the present invention are possible in the light of the above teachings. It is therefore to be understood that within the scope of the appended claims, the invention may be practiced otherwise than as specifically described.

What is claimed is:

1. In a magnetic relay, a fixed contact and a movable contact connected to an armature movable directly toward said fixed contact in response to the actuation of said relay, at least one of said contacts comprising an arcuate leaf spring with a flat side thereof in opposed relation to the remaining contact and touching said remaining contact over a predetermined area of arc, one of said contacts having a resistance varying from a very high predetermined value at said predetermined area of substantially zero at portions of said leaf spring contacting said remaining contact only when actuation of said relay compresses said spring, providing a substantially infinite resistance contact when the contacts are at their open-most position and a substantially short circuit contact when at their closed position.

2. In a magnetic relay, an elongated fixed contact, a pivotally mounted armature movable directly toward said fixed contact in response to the actuation of said relay, the said armature pivoting in a plane parallel to the length of said elongated fixed contact, and an elongated movable contact mounted upon said armature having a finite length in the same radial direction as said fixed contact and closing directly in opposed relation thereto upon the pivoting of said armature, at least one of said contacts comprising an arcuate compressible leaf spring convex toward and touching said remaining contact at a predetermined area of maximum resistance, one of said contacts having a gradient of resistance lessening to substantially zero resistance within the closed coterminous length of said contacts, whereby actuation of said relay compressing said spring produces rolling contiguity between said contacts proceeding from a very high resistance to a substantially complete connection between said contacts.

3. The device as recited in claim 2 wherein said lessening gradient of resistance is provided by a coating upon one of said contacts having immersed therein finely divided particles of a conductive material, said particles increasing in concentration away from the area of first contact.

4. In a magnetic relay, an elongated fixed contact, a

relay armature, actuating means for moving said armature directly toward said fixed contact in a plane parallel to the length of said elongated fixed contact, and an elongated movable contact mounted upon said armature having a finite length in the same direction as said fixed contact and closing directly in opposed relation thereto upon the actuation of said armature, at least one of said contacts comprising an arcuate compressible leaf spring secured at both ends thereof and convex toward and touching the remaining contact at a predetermined area of maximum resistance between said ends of the arc, one of said contacts having a gradient of resistance lessening from said area to substantially zero resistance within the closed coterminous length of said contacts, whereby operation of said armature compressing said spring produces a rolling contiguity between said contacts proceeding from a very high resistance to a substantially complete connection between said contacts.

5. In a magnetic relay, an elongated fixed contact, a relay armature, actuating means for moving said armature directly toward said fixed contact in a plane parallel to the length of said elongated fixed contact, and an elongated movable contact mounted upon said armature having a finite length in the same direction as said fixed contact and closing directly in opposed relation thereto upon the actuation of said armature, at least one of said contacts comprising a cantilever leaf spring convex toward and touching the remaining contact at a predetermined area of maximum resistance, one of said contacts having a gradient of resistance lessening to substantially zero resistance within the closed coterminous length of said contacts, whereby operation of said armature compressing said spring produces a rolling contiguity between said contacts proceeding from a very high resistance to a substantially complete connection between said contacts.

6. In a magnetic relay, a fixed contact and a movable contact, said movable contact being fixed to an armature and being movable directly toward said fixed contact in response to the actuation of said relay, each of said contacts comprising an arcuate leaf spring with the flat sides thereof in opposed relation to each other and touching each other over a predetermined area of arc, one of said contacts having a resistance varying substantially proportionately to its length from a very high predetermined value at said predetermined area to substantially zero at portions of said leaf springs contacting each other only when actuation of said relay compresses said spring.
